HEATING STOVE

Gustav Klein, Atlantic City, N. J.

Application March 23, 1943, Serial No. 480,257

1. Claim. (Cl. 126—242)

My invention relates to a new and useful heating stove and more particularly to a solid fuel burning space heating stove.

Due to the prevailing emergency, solid fuel burning stoves are being increasingly used as space heaters in the living quarters of a house, as distinguished from conventional central heating furnaces installed in cellars. Such stoves are being urged upon the public as a means of reducing fuel oil consumption.

One objection to the installation of such stoves has been the dissemination of fly ash when the ash pit door was opened and the grates were shaken.

It is therefore an object of my invention to produce an improved construction in a heating stove whereby the grates may be shaken to drop ashes into a removable but totally enclosed ash pan positioned below the grates, without any fly ash or dust escaping into the room where such stove may be positioned.

A further object is to produce a neat looking and inexpensive construction.

The full nature of the invention, the structure of the invention, the method of its operation and the objects which are attained thereby will be more clearly understood from the following specification and the accompanying drawing in which:

Fig. 1 is a perspective view of one form of a solid fuel burning space heating stove for which my invention is designed, the same being shown prior to the application of my invention thereto;

Fig. 2 is a fragmentary view in front elevation of the lower portion of the stove shown in Fig. 1 after it is equipped with means for preventing dissemination of fly ash, according to my invention;

Fig. 3 is a fragmentary horizontal sectional view taken on line III—III of Fig. 2;

Fig. 4 is a fragmentary enlarged sectional view taken on line IV—IV of Fig. 2;

Fig. 5 is a fragmentary vertical sectional view of the lower portion of the stove showing details of construction; and,

Figs. 6 and 7 are reduced fragmentary front elevational views showing the manner of operation of my invention.

Referring to the drawing and more particularly to Fig. 1, there is shown a solid fuel burning, space heating stove 10 of a magazine feed type having a stoking opening 12 adapted to be closed by a door 14. The body of the stove is surrounded by a skirt 16 which is spaced from the body proper 18 of the stove to form an annular air circulating space 20 which is open at the top and bottom. As

the air in this space is heated it rises and thus cold room air is drawn at the bottom to be heated and discharged into the room. At its lower end, the stove is provided with an ash pit, the access opening to which is closed by a door 22. Immediately above the ash pit is a grate ring 24 on which is rotatably mounted a main grate 26 which is adapted to be arcuately reciprocated by a handle 28. The grate 26 is provided with a dump opening 27 which is normally closed by a round sliding grate portion 30 which is connected to the inner end of the handle 28. When it is desired to shake the grate it is merely necessary to move the handle 28 arcuately to and fro. When it is desired to dump the ashes, the handle 28 is pulled out to move the grate portion 30 out of registration with the opening 27, as shown in Fig. 5. In the ash pit is a removable pan 32, provided with a handle 34, which folds into the pan as shown in Fig. 5. It will be noted in Fig. 1 that there is a space between the upper edge of the pan 32 and the upper edge of the ash pit opening through which ashes fly out into the room when the grates are shaken by moving the handle 28 from side to side or in and out.

In order to eliminate this condition, I close the space above the upper edge of the pan 32 with a fixed strip 36 provided with angularly disposed portions 38 which are suitably secured to the wall of the ash pit, as at 39. The strip 36 is provided with a slot 40 through which the handle 28 extends and the ends of which limit the to and fro arcuate motion of the handle 28. The slot 40 is permanently closed by a movable strip 42, which has an opening 41 through which the handle 28 extends. The strip 42 is longer than the opening 40 and is slidably mounted in brackets 44 or the like carried by the fixed strip 36, as shown in Figs. 3 and 4.

When the handle 28 is moved to the left, the strip 42 moves with the handle from the position shown in Fig. 2 to that shown in Fig. 6. Conversely, when the handle is moved to the right, the strip 42 moves from the position shown in Fig. 2 to that shown in Fig. 7. In these positions, as well as in the central position, the slot 40 is closed by the strip 42 so that no dust flies out into the room as the grate is shaken by to and fro arcuate movement of the handle. Likewise, when the handle 28 is moved in and out to dump the ashes through the opening 27, the handle slides through tight-fitting registering openings in the strips 36 and 42. The lower edge of the strip 36 overlaps the upper edge of the pan 32 to make a tight joint and the upper and side edges of the strip 36 are

constructed so as to make tight contact with corresponding surfaces of the ash pit wall and openings.

As will be seen from Fig. 5, the handle 28 projects outwardly beyond the vertical plane of the outer edges of the ash pit opening only when the circular grate 30 is moved outwardly to leave the dump opening 27 in the center of the grate ring 26, unobstructed, for dumping cinders and the like through the opening 27. However, it will be seen that if the circular grate 30 is moved inwardly (to the right of Fig. 5) until it closes the opening 27, the outer end of handle 28 will be within or to the right of the vertical plane of the outer edges of the ash pit opening. The handle 28 is, therefore, in an out-of-the-way position and permits of the closing of the ash pit door 22 except when said handle is pulled out to dump the ashes.

It will thus be seen that in order to provide a removable container 32, of the type set forth, in a stove of the type set forth, and in order to permit of shaking the grate bars, the container must necessarily be of smaller vertical dimension than the ash pit opening. Therefore, ashes will fly into the room whenever the grate bars are shaken. By my invention, a very simple and inexpensive arrangement is provided, by means of which the escape of ashes into the room is effectively stopped. It will also be seen that the entire invention is carried out by the use of two pieces of thin sheet metal, namely, the strip 36, having the slot 40 and the deflected members 38 which are suitably secured in the interior of the ash pit, and the inner strip 42, which is movable with, and through which the handle 28 extends.

By my invention, it is possible to use a stove of the type illustrated in the living quarters of a house without danger of fly ash dirtying the floor and furniture every time the grates are shaken. I might add that the type of stove illustrated is especially adapted for use in a living room so that the stack 48 of the stove may be connected to the chimney of the fire place, and it is therefore essential that means be provided

against escape of fly ash into the room. It is to be noted that I have accomplished this result by a simple and inexpensive construction which requires a minimum use of metal since the strips 36 and 42 are made of scrap sheet metal which is left over from the manufacture of the stove, the body 18 and circulating jacket 16 of which are made of sheet steel.

What I claim is:

10. The combination with a stove of the character described which includes a grate, a horizontally-disposed shaker bar carried by the underside of said grate, and an ash pit below said grate, there being an access opening in a wall of said stove 15 affording access to said ash pit, of an ash pan disposed in said ash pit below said grate and removable through said opening, said pan being of the same width as, but of less depth than the depth of said opening, whereby the major lower 20 portion of said opening is closed by a wall of said pan and whereby a space remains between the top edge of said pan and the top edge of said opening into which the outer end of said bar extends, and means for closing said space comprising, a first strip fixedly secured to a wall of said 25 stove and extending from the top edge of said opening to the top edge of said pan, completely to close said space, there being an elongated slot in said strip through which the outer end of said 30 shaker bar extends and in which said shaker bar is freely movable in transverse and longitudinal directions, a second strip at least twice as long as said slot in said first strip disposed along the inner side of said stationary strip in registration 35 with and closing said slot in all positions, said second strip having an opening therein closely fitting said bar and through which said shaker bar is longitudinally movable, means for slidably supporting said movable strip for transverse movement with said bar and a door mounted at a 40 margin of said opening and coextensive in dimensions with the entire opening whereby in closed position said door encloses the front wall of the pan and the first strip.

GUSTAV KLEIN.
